DOLLY FOR MOVING COLUMNS

George Delbert Hulbert and Raymond Emory
 Conaway, Los Angeles, Calif., assignors to
 Twentieth Century-Fox Film Corporation, Los
 Angeles, Calif., a corporation of New York

Application August 16, 1943, Serial No. 498,788

5 Claims. (Cl. 280—41)

This invention relates to a dolly designed for lifting and moving loads such as posts, columns, etc.

The invention to be described hereinafter has been designed and constructed to meet requirements arising in the motion picture business particularly, but it will become apparent to those skilled in the art that it will have usefulness in other fields as well.

In the motion picture business it is common practice to store parts of buildings that have been used in previous pictures. Some of this material, such as columns, facades, etc., are stored as units so that they may again be used intact. Under these conditions it often happens that an ornate column must be moved from the set to storage and, since the column will be used again, it is desirable that it be moved without marring or damaging. The dolly embodied in this invention has been provided for this purpose and by virtue of its construction will lift the column from the floor and will carry it in a substantially upright position with practically no handling of the column itself. Under normal conditions the dolly may be operated by one man after it has been loaded. The principle of the dolly embodies an A-frame construction wherein the members of the A-frame are pivoted so that the angle between the two members may be changed to form a lifting device out of the dolly as well as a carrying means.

Other objects and advantages will become apparent as the description proceeds in conjunction with the drawing in which:

Figure 1 is a perspective view of the dolly without any load;

Figure 2 is a view of the dolly retracted and in a loading position ready to pick up a column; and

Figure 3 is a view of the dolly in an extended position showing a column carried thereon.

As stated, the dolly embodies an A-frame construction which is shown and exemplified by the members generally designated 11 and 12. The member 11 may consist of a single piece of pipe bent into a form to produce legs 13 and 14 which are connected at the upper end by a curved portion 15, the purpose of which will become later apparent. The member 12 may comprise two sections of pipe 16 and 17 which are pivotally connected to the legs 13 and 14 as shown at 18. The members 13 and 14 are mounted upon a cross member 19 while the members 16 and 17 are mounted upon the cross member 20. To render the device more useful, both the members 19

and 20 are mounted upon casters 21, all of which may be swivel casters or only a pair of which may be swiveled to provide for steering. Also mounted on the member 19 is a pair of angle plates 22 which are adapted to come close to the floor level as shown in Figure 2 when the dolly is retracted in a loading position. The column C may then be tipped slightly as shown by the dotted axis line X which allows the plates 22 to be shoved under the footing of the column. This part of the loading may require two men in case the column cannot be tipped slightly by the single man operating the dolly. However, once the members 22 are beneath the column, one man may tip the column slightly inward toward the member 11 and secure it in position by a rope or equivalent member 23 which is secured to the members 13 and 14 by means of eyelets 24. The top of the column will be held in position by the curved member 15. In cases where a short column may be handled, we have provided a second curved member 25 extending between the members 13 and 14 similar to the member 15. As a means of holding the members 11 and 12 in either a retracted position for loading or an extended position for carrying, we provide strap members 26 and 27 which are pivoted to the members 13 and 14 respectively and held together at their outer ends by a cross rod 28. These members are provided with notches 29 and 30 designed to engage lugs 31 on the members 16 and 17 respectively. Figures 2 and 3 show the two positions of the dolly and how the members 26 and 27 hold it in these two positions. As an added precaution we may provide an additional holding means 32, which in this instance is shown as a rope extending between the members 19 and 20. This member is only in case the other members fail to hold and has been added only in the interest of safety.

In operation the dolly may be brought up to a column to be moved and retracted to the position shown in Figure 2. It is locked in this position by the members 26 and 27 as shown. The column is then tilted as indicated by the line X and the plates 22 shoved beneath the column. The column is tilted back against the dolly and is tied into place by the rope 23. The operator then moves around behind the dolly and lifts the members 26 and 27 so that the notch 29 clears the lug 31 and with his feet on the cross member 20 pushes against the bar 28 connecting the outer ends of the members 26 and 27, thereby spreading the A-frame, which leans the column farther back and raises the base of the

column from the floor, thus putting the entire load on the dolly. This brings the slots 30 in the members 26 and 27 over the lugs 31 and the members are dropped into place, thus locking the dolly in the carrying position. The column in this position may be moved about wherever desired. The operation is simple, fast, and requires no more than two men in an extreme case and can generally be done by one man. The device is simple, inexpensive, and durable.

We are aware that modifications and refinements of construction in the device may be made without departing from the invention. Accordingly, the disclosure made herein is intended to cover all equivalent means for the purpose described.

We claim:

1. A dolly for moving columns or the like comprising a front member mounted on a movable support, a back member pivoted to said front member, the lower end of said back member being mounted on a movable support, flat plates extending from the lower end of said front member adapted to be lowered substantially to a floor level and be slipped beneath a column footing when said back member is retracted into a loading position, means on said front member for securing a column thereagainst so that it will be tilted therewith, and means for locking said back member in a retracted position for loading, and in an extended position whereby said front member is tilted so that said column is raised on said plates and supported in an inclined position on said dolly.

2. A dolly for moving columns or the like comprising an elongated front member having flat plates extending from the lower end thereof, means for securing said column against said front member, a rear member pivotally mounted at one end to said front member so that movement of said rear member on its pivot point changes the inclination of said frame, means for locking said rear member in a position whereby said front frame is tilted forward so that said plates come substantially to the floor level for slipping under the column footing, and means for locking said rear member in another position whereby said front frame is tilted backwards

and the said plates are raised from the floor to lift and support said column on said dolly in an inclined position.

3. A dolly for moving columns or the like comprising a front member and a back member pivoted together to form an A-frame construction, flat plates extending at right angles from the lower end of said front member, means for holding said members in a retracted position so that 10 said plates are lowered substantially to the floor level for sliding beneath the base of said column, and means for holding said members in an extended position whereby said plates are raised from the floor level and the column is carried 15 upon said frame in an inclined position.

4. A carrier for moving columns or the like comprising an inverted U-shaped member having flat plates extending from the lower end thereof, the upper end of said U-shaped member 20 being shaped to form a supporting cradle for a substantially upright load, a back member pivotally connected to said front member to provide an A-frame construction, means for holding said back member in a retracted position 25 with respect to said front member so that said plates will be lowered substantially to the floor level for sliding under a load, and means for holding said back member in an extended position with respect to said front member to raise 30 said load and support the same in an inclined position upon said plates and said supporting cradle.

5. A lift carrier comprising a front member and a back member pivotally inter-connected to 35 form an A-frame construction, flat plates extending from the base of said front member adapted to be lowered substantially to the floor level for sliding under a load when said front member is in a substantially upright position 40 and will lift said load when said front member is in an inclined position, and means for holding said back member with respect to said front member to dispose said front member in a substantially upright position, or in an inclined 45 position whereby said load may be lifted and supported upon said carrier.
